CONNECTION BLOCK TERMINAL

Alfred R. Kuhn, Queens Village, N. Y., assignor
to Metropolitan Device Corporation, Brooklyn,
N. Y., a corporation of New York

Application April 4, 1935, Serial No. 14,723

2 Claims. (Cl. 173—324)

This invention relates to electrical apparatus provided with terminals for the attachment of cables, such as connection blocks, switch blocks, fuse blocks and the like. In a specific application of the invention it relates to a connection block providing for the ready making and breaking of a circuit (for meter testing for example) with a minimum of resistance and at the same time with secure connections to the cables. The invention also relates to terminals which are peculiarly adapted as elements of connection blocks and the like for receiving cable ends.

A terminal of the clamp type is preferable to a soldered one as the serious objections of heating required to make a soldered connection, limited heat resistance and relatively high current resistance are thereby avoided. With the clamp type of terminal, however, a tight grip on the cable which will not loosen with vibration is essential.

The present invention provides a terminal of the clamp type adapted for connection blocks and the like which is economically constructed yet rugged and suitable for securing cables of relatively large size. In brief the terminal has for its dominant feature concentrated pressure contact or bearing areas for firmly gripping a cable without loosening. This is obtained by providing a terminal for a bar fitting, the terminal having an opening to receive the cable end and having as a part thereof a threaded stud on which is movably mounted a clamping member that is guided and held from turning by the terminal and means coacting with the stud for forcing the clamping member edges against the cable end. Further accentuation and concentration of pressure can be obtained by a kink or wave formed in the cable-contact surface on the bar and/or conforming the clamping member edges to the cross section of the cable end. The bar which is so provided with a terminal formed with a threaded stud and cable receiving opening can be a current-carrying bus bar or the equivalent of a connection block or other piece of electrical apparatus.

Fig. 1 illustrates in perspective an upstanding end member forming part of the terminal;

Fig. 2 is a perspective view of a bus bar construction for engaging the end member of Fig. 1; 50 Fig. 3 shows in perspective a modification of the bus bar of Fig. 2;

Fig. 4 is a horizontal cross sectional view on the line 4—4 of the end member of Fig. 1 with the bus bar of Fig. 3 inserted and projecting shoulders headed over;

Fig. 5 illustrates in vertical cross section the terminal end member of Fig. 1 on the line 5—5 but showing the bus bar inserted and the bottom cross piece of the end member pressed into a cavity in the bus bar;

Fig. 6 is a view in perspective of a clamping member for mounting on the terminal end member of Fig. 1;

Fig. 7 is a perspective view of a nut for engaging the threaded stud of the end member to force 10 the clamping member into gripping contact with a cable end;

Fig. 8 is a view in vertical cross section of a connection block showing the parts in assembled relation and securing a cable; and 15

Fig. 9 is a plan view of a block showing an assembly of separable terminal end members on a single conductive bar fitting.

The terminal comprises a bus bar 100 with a separable upstanding end member for engaging 20 the end 101 of the bus bar and provided with an opening for receiving a cable; the upstanding member carries clamping means whereby the cable is gripped against the bus bar. As illustrated in Fig. 1 the end member consists of a flat 25 bar portion 102 with an integral threaded stud 103. It is slotted as at 104 thus forming a yoke 105 to receive an extended end or tongue 105 of the bar. A cable-receiving opening 106 can be formed as an extension of the slot. The bar fitting is provided with shoulders 107 to engage 30 the flat portion 102 of the terminal. When the terminal and the bar fitting are assembled the bar provides a bearing surface 108 for a cable 35 and the extension 105 likewise affords a cable supporting surface; this is illustrated in the assembly of Fig. 8. Between these two surfaces there can be formed a hump 109 to cause a kink 40 in the clamped cable and concentrate the bearing contact.

The separable bar fitting for engagement with the terminal 100 can be given a modified end formation as shown in Fig. 3. In this formation the reduced end 110 provides shoulders 111 to contact the flat portion 102 of the terminal and also with additional shoulders 112 forming a further contracted end 113. In assembling the end 113 is inserted in the slot 104 and the shoulders 112 swaged or headed over as shown in Fig. 50 4 to securely hold the terminal to the bar fitting. The cable receiving surface 114 can be knurled as at 115 to give an increased gripping action. The terminal 100 can be further secured to the bar fitting by providing the under surface of the 55

bar with a cavity 116 and pressing the cross piece 117 of the terminal into the cavity.

The assembly illustrated in Fig. 8 provides a connection block having a base 130 of insulating material. On the base there is mounted the bus bar or strap 101, preferably flat and of copper, and this can be secured to the block by such means as screws 131, 132. The upstanding end member 100 is slipped over the end 105 of the bar which extends through the slot 104. A U-shaped clamping member 133, shown in perspective in Fig. 6, has an opening 134 for freely engaging the stud 103. The clamping member is made partly cylindrical to accommodate the stud, and the cable-engaging ends can be curved as 135, 136 or otherwise shaped to contact a cable. A threaded nut 137 engages the stud for operating the clamping member.

A cable 140 that is to be clamped to the terminal has its insulating cover removed for a distance to expose the conducting strands 141. The exposed strands are inserted in the opening 106 and the nut 133 is turned to press the clamp into tight contact with the conductor. The clamp forces the cable against the bearing surface 108 of the bar at one side and against the extension 105 at the other side of the member 100. In order to position the cable in the connector block a screw 131 can be extended to provide a stop 142. By these means the cable is positioned and then firmly secured by clamping on both sides of the yoke portion 102 of the member 100 to furnish a concentrated grip sufficiently strong to sustain the weight of the cable when suspended as a vertical riser in a raceway.

The flat portion 102 of the upstanding member, in addition to receiving a cable conductor, can be given the function of serving as a guide for the clamping member 133 to prevent its turning by shaping the clamping member so as to contact the sides of the bar. This construction insures an effective grip upon the cable as there is no rotation or sliding of the member over the cable surface. The integrally formed stud 103 also supplies a convenient means for

additional temporary or permanent connections such as those used for taps to a main or for a meter tester.

More than one separable terminal can be secured to a bar fitting. This is illustrated in Fig. 9 where six separable terminals are attached to one fitting 120. Such a fitting can be attached to a block or other apparatus by screws 121 for example, which screws also form stops for the cable ends.

While the preferred forms of the invention have been illustrated, it is to be understood that other modifications can be made and that accordingly no restriction on the invention is intended except as defined in the following claims.

What is claimed is:

1. Terminal for receiving a cable comprising in combination a bar fitting having a perforation therethrough for a cable, a U-shaped clamping member embracing the flat sides of the bar fitting and coacting with said fitting to provide ends for gripping a cable inserted through said perforation, said clamping member being guided against turning by its engagement with the sides of the fitting, means for operating the clamping member, a bar approximately at right angles to the fitting, and means securing said bar to the fitting, said means including a slot in one of the two elements and a tongue on the other extending into the slot.

2. Terminal for receiving a cable comprising in combination a bar fitting having a perforation therethrough for a cable, a U-shaped clamping member embracing the flat sides of the bar fitting and coacting with said fitting to provide ends for gripping a cable inserted through said perforation, said clamping member being guided against turning by its engagement with the sides of the fitting, means for operating the clamping member, a bar approximately at right angles to the fitting, and means securing said bar to the fitting, said means including a slot forming a continuation of the perforation in the fitting and a tongue on the bar extending into the slot.
